UNITED STATES PATENT OFFICE

CHARLES A. FINLEY, OF RUTHERFORD, NEW JERSEY, ASSIGNOR TO BOORUM & PEASE COMPANY, OF BROOKLYN, NEW YORK, A CORPORATION OF NEW YORK

LOOSE-LEAF POST BINDER

Application filed April 4, 1927. Serial No. 180,970.

This invention relates to loose leaf post binders and more particularly to loose leaf post binders in which the posts project through the hollow top clamping bar. One object of my invention is to provide a binder which is neat in appearance, economical to manufacture, easy to assemble and so constructed as to withstand shocks. Another object of the invention is the provision of a binder which can be made in various sizes from one common stock of parts. In the type of binder to which the invention relates, the posts on which the sheets are threaded are mounted in a lower clamping bar and project through an upper clamping bar, the latter having locking means therein adapted to prevent removal of the clamping bar.

In this type of binder it has been customary to make the clamping bar of hollow or rolled tubular material and it has been difficult to assemble the locking means in the bar. The process of assembling the device has also been expensive and the manufacture of different sizes of binders has required the carrying of different stock for each size. It has been discovered that great economies can be effected in the cost of material and methods and time of assembly and a stronger binder produced if the following novel construction of clamping bar is employed.

In the drawings,

Fig. 1 is a perspective view of a binder, embodying the invention;

Fig. 2 is a transverse elevation partly in section through the clamping bars taken on the line 2—2 of Fig. 3;

Fig. 3 is a longitudinal elevation partly in section through one end of the clamping bar taken on the line 3—3 of Fig. 2;

Fig. 4 is a plan view of one end of the top clamping bar taken on the horizontal section line 4—4 of Fig. 2;

Fig. 5 is an exploded perspective view of one end of the clamping bars;

Fig. 6 is a cross section of a modified form of clamping bar; while

Fig. 7 is a similar cross section of a further modified form.

According to this invention each clamp-

ing bar includes an angled metal strip having at least two walls and preferably consisting of a three-sided channel iron, and a hinge plate therefor which when assembled together constitute the four walls or faces of the clamping bar. In the preferred embodiment shown in Figs. 1 to 5 of the drawings the upper clamping bar consists of a U shaped channel iron 11 open at the bottom and a flat hinge plate 12 adapted to be fastened to the channel iron by means of rivets 13 taking into the channel iron thus closing the latter. The two edges of the channel iron are rabbeted in order that the hinge plate may set in the rabbets 24 and be flush with the ends of the channel iron. There are hinge knuckles or lugs 14 on the hinge plate 12 which provide means for attaching a cover 15 to the clamping bar. These lugs interlock with the rabbets 24 thus maintaining the plate in its proper lengthwise position. The hinge plate also carries the individual locks 16 which constitute the means for locking the upper clamping bar on the posts 17. In the drawings the locks are shown attached by means of screws 23. In each end of the channel iron is fitted a solid end cap 18 and one of the rivets 13 can be passed through the hinge plate 12 and end cap 18 into the channel iron 11 thus fastening the three elements together. Thus two rivets, one at each end of the clamping bar, can serve to assemble the whole structure although an additional rivet or two can be placed in the middle of the channel iron if desired.

In the embodiment shown in the drawings the individual locks are of the pivoted clutch type operable from the top of the clamping bar by pressing downwardly on a button 19 projecting through the top of the channel iron. These buttons operate on the pivoted clutch members 20 which form part of the locks 16 screwed to the cover plate 12.

It will be perfectly obvious that the lower clamping bar may be constructed in identically the same manner except of course that instead of locks fastened to the hinge plate the posts 17 are screwed to the hinge plate or passed through the same, mounted on blocks 21 therein, or fastened to the clamping bar in any other suitable manner. The blocks

21 may be fastened to the hinge plate or to the channel iron as desired.

The channel iron or angled strip can be made of extruded metal such as aluminum or cold rolled steel and can be cut to any length according to the desired size of binder, thus making it possible to use one and the same stock of material for binders of all sizes.

In binders of this type it is frequently 10 desirable to cover one or both of the metal clamping bars with some form of cloth and in such case the novel construction already described can be availed of to unusual advantage. To cover the clamping bar cover 15 material 22, such as cloth, is wrapped around the channel iron and the two longitudinal edges laid over the rabbets 24 on the legs of the channel iron. When the hinge plate is laid in the rabbets and fastened to the channel iron, the cover material is stretched and held in position and its edges kept out of sight. The rivets can pass through the cover material, as shown in Fig. 2, if desired. If it is desired to cover the hinge plate as well, then 25 a second piece of cover material can be stretched and held in a similar manner. It should be noted that if the binder is dropped or receives a knock in any other manner, that blow will not fall on the element carrying 30 the hinge lugs and the locks but on the channel iron. The blow is also cushioned by the introduction of the cloth cover between the hinge plate and the channel iron.

The advantages of this construction with 35 regard to economy in time and cost of assembly will be obvious. In assembling the device heretofore it has been necessary to mount the locks inside the closed tube and in the type of binder illustrated in the drawings it has been particularly hard to assemble 40 the lock itself, the operating button projecting through the clamping bar and the clamping bar itself.

If desired, the angled metal strip may form 45 only two sides of the clamping bar as illustrated in Figs. 6 and 7. In Fig. 6 the angled strip 27 forms the top and inner walls, while the cover plate 26 forms the other two walls and carries the hinge lugs 14. In Fig. 7 the 50 angled strip 25 forms the top and inner walls and carries the hinge lugs 14, while the cover plate forms only the other two walls.

In assembling a binder made according to 55 the present invention the individual locks are fastened to the piece of material constituting the hinge plate. The channel iron or angled strip is turned upside down and the button put in its hole, the cover plate inverted, laid on the channel iron and fastened in position. 60 The whole device is thus assembled without any problem of fitting the parts together and there is no working in confined spaces. The ease in attaching the cloth cover needs no description and the neatness of the result will 65 be equally obvious. It will also be observed

that there is no projection of any kind which can be availed of to pry the parts of the clamping bar apart and the combined elements interlock with each other at all points. It might also be noted with regard to the hinge lugs that they are formed as part of the cover plate which is a flat piece of metal, thus insuring ease in manufacture, and that this element is so rigidly attached to the rest of the clamping bar that the hinge lugs can never be pulled out of position. The simplicity of the structure is obvious.

What I claim is:

1. A loose leaf post binder having a hollow clamping bar composed of a strip angular in cross-section having at least two walls, and a cover plate therefor, in combination with cover material for said clamping bar whose longitudinal edges are gripped between said angled strip and said plate. 80

2. A loose leaf post binder having a hollow clamping bar composed of a channel iron adapted to form three sides of said bar in combination with a hinge plate adapted to form the fourth side, hinge lugs integral with 90 said hinge plate and locking means for the posts mounted on said hinge plate.

3. A loose leaf post binder having a hollow clamping bar consisting of a U-shaped channel iron, a plate adapted to close the opening between the legs of said channel iron, in combination with cover material for said channel iron whose longitudinal edges are gripped between said channel iron and said plate. 95

4. A loose leaf post binder having a hollow clamping bar consisting of a U-shaped channel iron, a hinge plate fitting flush into the opening between the legs of said channel iron, and hinge lugs integral with said hinge plate in combination with cover material for said 100 channel iron whose edges are gripped between said channel iron and said hinge plate. 105

5. A loose leaf post binder having two hollow clamping bars with the posts adapted to project through one of said clamping bars, 110 each clamping bar comprising an angled metal strip, a hinge plate adapted to close the opening between the legs of said metal strip and having hinge lugs integral therewith, and individual locks attached to the hinge plate of the upper clamping bar, in combination with buttons for operating said individual locks projecting through openings in the top of the angled strip of the upper of said clamping bars. 115

In testimony whereof I have signed my name to this specification.

CHARLES A. FINLEY.
